UNITED STATES PATENT AND TRADEMARK OFFICE
CERTIFICATE OF CORRECTION

PATENT NO. : Des. 395,157
DATED : June 16, 1998
INVENTOR(S) : Peter von Conta

It is certified that error appears in the above-identified patent and that said Letters Patent is hereby corrected as shown below:

On the cover page,

after the individual Figure Descriptions insert:

--The broken line showing of a shoe upper in Figures 1-5 is environmental only and forms no part of the claimed design.--

Signed and Sealed this
Eighth Day of September, 1998
